APPARATUS FOR EXTRUDING METAL

Charles Sandell Farmer, deceased, late of Welwyn Garden City, by Bertha Frances Farmer, executrix, Welwyn Garden City, and Charles James Beaver and Thomas James Fairfield, Bowdon, England, assignors to W. T. Glover and Company Limited, Manchester, England, a British company

Application November 5, 1937, Serial No. 172,944
In Great Britain November 24, 1936

3 Claims. (Cl. 207—2)

This invention relates to that type of apparatus for the extrusion of metal in which molten metal is fed into the outer part of a cylindrical container, is allowed to cool there and is then forced by a ram towards the inner end of the container, where it passes out in the plastic state by way of a die or dies. In such apparatus, after the working stroke has been completed, the ram is drawn back relative to the container and the further charge of molten metal is fed in to the space between the ram and the remaining part of the previous charge at the inner end of the container. It will be seen that the operation of this apparatus is intermittent and it has been recognized that this kind of operation has many disadvantages.

By arranging two or more containers (each with its ram) to deliver into a single space, which may be spoken of as an extrusion chamber, from which the plastic metal passes into the die and by making the working strokes of the rams at the appropriate time intervals it appears possible to produce a continuous output from the apparatus. But in order to do this it is necessary to provide some means to prevent the working stroke of one ram from forcing back metal into a container from which the ram has been withdrawn for the purpose of re-filling the container with molten metal. The metal in the delivery end of each container, and in the extrusion chamber, and the passages between this and these, is in the plastic state. Accordingly, no ordinary mechanical valve can be used to prevent the backward movement of the material.

The present invention supplies an effective means of restraining the metal in the extrusion chamber from being forced back into a container when the pressure therein is reduced so that an effective multi-container press of the type indicated can be produced. In accordance with the invention the backward movement is restrained by providing a particular form of passage between each container and the common extrusion chamber, this passage being such that the metal flows easily from each container into the extrusion chamber, but is effectively prevented from moving to any substantial extent in the opposite direction.

It has been found that under the ordinary working conditions of pressure and temperature and rates of movement which are used in extrusion apparatus of the kind indicated, a passage of tapered form offers much greater resistance to a flow in one direction than in the other. The comparatively free direction of flow is that in

which the plastic metal enters at the smaller end of the tapering passage and leaves at the larger end. The reason for this difference in action appears to be that the end of the passage at which the metal enters acts as a die to fix the dimensions of the cross-section of the stream of metal. When the metal enters at the smaller end a rod is produced which can move freely through the increasing section of the passage. When the direction of movement is reversed the rod produced at the larger end strongly encounters the walls of the passage and is compressed thereby, thus producing very considerable resistance to flow.

In the further description of the invention, reference will be made to the accompanying drawings, of these,

Figures 1 and 2 are curves relating to the proportions of the passage;

Figure 3 is a side elevation with half in section of a press embodying the invention;

Figure 4 is a plan view of the central part of Figure 3; and

Figure 5 is an enlarged view in section of the central part of Figure 3.

The effect of the proportions, namely degree of taper, length of passage and area of cross-section, affect very materially the obtaining of this automatic differentiation between directions of flow.

This is shown by the curves in Figures 1 and 2 of the drawings. In these figures the vertical scale shows the reduction in the speed of extrusion which takes place when the direction of extrusion is reversed. This reduction is expressed as a percentage of the speed of extrusion when the metal is moved from the small to the large end of the tapered passage. These curves are intended to give primarily indications of the effects of the changes of the quantities indicated on the horizontal scales. Their shape is regarded as of greater importance than the precise values which they indicate. These may be varied by different experimental conditions such as the nature and finish of the surfaces of the passages. The general shapes are, however, believed to be representative and enable conclusions to be drawn, in such a way as to determine a satisfactory design of the passage as well as indicating its effectiveness for the purpose in view. The curves were obtained by experiments conducted with passages having dimensions such as are necessary for metal extrusion presses in current practice.

On the horizontal scale of Figure 1 is measured the taper of the passage. The passage is circular and the taper is measured as the change of

diameter in mils. for each inch length of the passage (or in hundredths of a millimetre for each centimetre length). To express it as a percentage it is clear that the figures of the scale 5 should be divided by ten. It will be seen that as the taper is increased the reduction in extrusion speed rises very rapidly at first and soon reaches a maximum, and then falls off much less rapidly. A taper of the order of 3 mils. change 10 of diameter per inch (or 3 hundredths of a millimetre per centimetre) length of passage gives approximately the maximum result, but the effect is not greatly reduced by a substantial increase 15 of taper, say, up to 9 mils. (hundredths of a millimetre) change of diameter per inch (centimetre) of length.

The horizontal scale of Figure 2 measures the ratio of the length of the passage to the minimum 20 diameter. It will be seen that the effect of increase of this ratio is great at first but decreases gradually as the curve proceeds. It is clear that the length of the passage should always be substantially greater than its diameter. Values of 25 from 3 to 8 times are within practically satisfactory limits, but the higher part of the range is preferable.

As a practical example it has been found that a passage of circular cross-section, 6 inches (15.24 cm.) in length and with inlet diameter 0.750 inch (19.05 mm.) and outlet diameter 0.768 30 inch (19.51 mm.) will provide for normal output from the container of a press of medium size and will produce a reduction in the speed of extrusion of 99.4%. That is to say, movement of lead in 35 the reverse direction in the passage under full delivery pressure will be restricted to about 0.6% of that in the direction of free flow under the same pressure, thus effectively producing a non-return action.

40 In Figures 3 to 5 of the drawings is illustrated a two-container press in which the lead is driven alternately by the two rams into the common extrusion chamber through tapering passages having proportions such as given in the practical 45 example above. The passages 3 leading from the containers 4 to the extrusion chamber 5 are circular in section and have the diameter at the point 2 measuring 0.750 inch (19.05 mm.) and the diameter at the point 1 measuring 0.768 inch 50 (19.51 mm.) and the distance between the points 1 and 2 measuring 6 inches (15.24 cm.).

The ram 6 for each of the two containers 4 is connected at the rear end to the plunger 7 which works in the hydraulic cylinder 8. Packing 55 pieces 23 are provided in the usual manner to prevent the escape of fluid from the hydraulic cylinder 8 and to prevent the movement of fluid past the plunger 7 from one compartment to the other within the cylinder. That part of the 60 surface of the plunger 7 which moves in and out of the cylinder 8 and the interior surface of the cylinder are provided respectively with a cover 24 and a liner 25 of non-ferrous metal for protective purposes. These cylinders and the two containers 65 are carried by side brackets 9 and 10 respectively located by large nuts 26 on two side rods 11 which thus hold the parts of the press together. These rods 11 are supported by pedestals 12 which thus carry the weight of the press. 70

75 Between the two containers 4 is held the die box 13 in which are the passages 3 and the extrusion chamber 5 with the inner die 14 and the outer die 15. The arrangement of dies shown provides for the extrusion of a tube such as the

sheath 21 of a cable 22. When a cable is being sheathed it is fed upward through the bore of the inner die 14 as shown in Figure 3.

The method of working the press so as to obtain a continuous extrusion is as follows. With 5 the right-hand container 4 and ram 6 in the condition shown in Figure 3, this container is full of metal which has been poured in in the molten state by means of an inclined chute 19, the delivery end of which is applied to an entry port 10 20 provided in the end of the container, the chute being afterwards removed. The metal in the container has been allowed to stand until it has sufficiently solidified at the end in contact with the end of the ram 6 to permit this to transmit a steady pressure to the body of metal in the container. At this point the forward movement of the ram 6 is commenced by the admission of water under pressure behind the plunger 7 15 through the pipe 16. 20

At this stage the ram 6 in the left-hand container has reached the innermost point of its stroke which is about the position indicated by the arrow 17 in the right-hand container. As the ram 6 of the right-hand container 4 commences to move inward, the ram of the left-hand container is withdrawn quickly by the admission of water under pressure to the cylinder 8 by way of the pipe 18 so that it acts upon the annular front face of the plunger 7. This withdrawal 30 of the ram from the left-hand container leaves the outer part of the container empty, with a body of plastic metal at the inner end of the container and in the passage 3. When the left-hand ram has been completely withdrawn the 35 molten metal is run into the container, by means of a chute as described above, and allowed to cool until the desired solidification near the end of the ram has taken place so that the forward stroke can be commenced. By proper adjustment of conditions this retraction and refilling 40 and preliminary cooling can be made to occupy substantially the time of the working stroke of the ram in the right-hand container so that the latter may be withdrawn when the left-hand ram 45 commences its forward stroke. By a series of alternating working strokes in this way the two rams may produce a substantial continuous extrusion of metal from the chamber 5 between the dies 14 and 15. 50

It will be seen that during the extrusion process the metal in the chamber 5 is continuously under the extrusion pressure, and that movement of metal into the chamber takes place alternately from the right and left-hand passages 3 (Figure 55 5). While one of these passages is feeding the chamber the metal in the other passage is at the point 1 subjected to the full extrusion pressure, and this is not resisted within the container since the ram is withdrawn for re-filling at this 60 stage. It is found, however, that the taper of the passage 3 in the manner indicated suffices to prevent any appreciable backward movement of the metal through the passage into the container. 65

It will be understood that more than two containers can be used if desired and that many ways of grouping the containers in relation to each other are available. The drawings show by way of example only, a convenient arrangement of a two-container press. 70

What we claim as our invention is:—

1. An extrusion press for metal, comprising a plurality of containers, a single extrusion chamber, means for forcing in succession metal from each container into the said extrusion chamber 75

and connecting passages between each container and the extrusion chamber, each passage having a small taper and having its larger end near to the extrusion chamber, by reason of which each passage acts as a non-return device for the plastic metal.

2. An extrusion press for metal, comprising a plurality of containers, a single extrusion chamber, means for forcing in succession metal from each container into the said extrusion chamber and connecting passages between each container and the extrusion chamber, each passage having a small taper and having its larger end nearer to the extrusion chamber, by reason of which each passage acts as a non-return device for the plastic metal, the taper, measured as change of diameter in unit length of the passage, being between 0.2% and 0.9% of unit length.

3. An extrusion press for metal, comprising a plurality of containers, a single extrusion chamber, means for forcing in succession metal from each container into the said extrusion chamber and connecting passages between each container and the extrusion chamber, each passage having a small taper and having its larger end nearer to the extrusion chamber, by reason of which each passage acts as a non-return device for the plastic metal, the length of each passage being from three to eight times its diameter. 5
